DESIGN FOR A BRACELET OR SIMILAR ARTICLE

Benjamin F. Conner, Wethersfield, Conn., assignor to Colt's Patent Fire Arms Manufacturing Co., Hartford, Conn., a corporation of Connecticut

Application August 24, 1933, Serial No. 49,100

Term of patent 7 years

To all whom it may concern:

Be it known that I, BENJAMIN F. CONNER, a citizen of the United States, residing at Wethersfield, in the county of Hartford and State of Connecticut, have invented a new, original, and ornamental Design for a Bracelet or Similar Article, of which the following is a specification, reference being had to the accompanying drawing.

In the drawing:

The figure is a perspective view of a bracelet embodying my new design.

In the drawing the stippled and unstippled portions respectively represent different contrasting colors, but are not intended to represent any specific colors.

I claim:

The ornamental design for a bracelet or similar article as shown and described.

BENJAMIN F. CONNER.
